J. HAAS.

HOLDER FOR CONES OR SPOOLS OF ARTIFICIAL SILK AND OTHER THREAD.

APPLICATION FILED JUNE 11, 1915.

1,168,393.

Patented Jan. 18, 1916.

UNITED STATES PATENT OFFICE.

JOSEPH HAAS, OF MARTINSBURG, WEST VIRGINIA, ASSIGNOR TO INTERWOVEN MILLS, INC., OF NEW BRUNSWICK, NEW JERSEY, A CORPORATION OF NEW JERSEY.

HOLDER FOR CONES OR SPOOLS OF ARTIFICIAL-SILK AND OTHER THREAD.

1,168,393.

Specification of Letters Patent.

Patented Jan. 18, 1916.

Application filed June 11, 1915. Serial No. 33,446.

To all whom it may concern:

Be it known that I, JOSEPH HAAS, a citizen of the United States, residing at Martinsburg, in the county of Berkeley and State of West Virginia, have invented certain new and useful Improvements in Holders for Cones or Spools of Artificial-Silk and other Thread; and I do hereby declare the following to be a full, clear, and exact 10 description of the invention, such as will enable others skilled in the art to which it app pertains to make and use the same.

My invention consists in the novel features hereinafter described, reference being 15 had to the accompanying drawing which illustrates one embodiment of the invention selected by me for purposes of illustration, and the said invention is fully disclosed in the following description and claims.

20 Referring to the said drawing: Figure 1 represents a vertical sectional view of a thread holding device embodying my invention, and Fig. 2 represents a top plan view of the same.

25 My invention is especially adapted for holding cones, spools or bobbins of artificial silk, although obviously it can be used for holding cones, spools or bobbins of any other kind of thread.

30 Artificial silk, as is well known differs materially in character from pure silk or natural silk, especially in two important particulars which affect its handling and use in manufacturing fabrics therefrom. In the

35 first place it has very much less tensile strength and in the second place it is stiff and wiry in character as compared with pure silk and other threads. Artificial silk, like other threads, when spun into thread is ordinarily sold to the trade in skeins and is wound upon "cones", usually in the form of hollow truncated cones of paper, papier mâché, or paste board, or upon spools or bobbins before it can be used for manu- 45 facturing textiles.

Where the silk is wound on cones it is frequently re-wound therefrom upon spools or bobbins adapted for use with textile machinery and which usually do not hold as great a length of thread as the cone. The cones ordinarily hold several skeins in which the thread is continuous and it is therefore advantageous to use the silk directly from the cone as it eliminates a certain number of splicings of the thread and saves the expense

of re-winding and the splicings particularly in artificial silk are liable to cause trouble in knitting or weaving the thread in the manufacture of textile fabrics. As my invention is equally applicable to holders for 60 cones, spools and bobbins, I use these terms interchangeably except where specially noted, as applying to the device of whatever character it may be, upon which a body of thread is wound. In drawing off the silk 65 from these cones, spools or bobbins, if the tension is relaxed at any time, the thread tends to spring away from the body of thread on the cone or spool for as many convolutions as the degree of slackness permits 70 and to slide down the exterior surface of the body of thread, as the thread is hard and glassy, and does not cling to the body of thread as would a thread of silk, wool, or cotton, for example. It, therefore, frequently happens that one or more convolutions of the thread fall below the spool and when the thread is drawn taut it catches under the spool or under the support for the same and quickly breaks. For this reason 75 it has been practically impossible commercially to draw off artificial silk directly from the cones which hold a large quantity of it, and it has been found necessary to use special spools holding smaller quantities in connection with weaving, knitting and other industrial operations and even in such cases considerable difficulty has been encountered 80 in handling the artificial silk.

In carrying out my invention, I provide 90 means for supporting the cone or spool and in connection therewith, I provide adjacent to the bottom of the cone or spool means for positively preventing a loosened portion of the thread from passing under and catching 95 under the lower edge of the spool or the lower surface of the body of thread thereon, and in connection therewith I also prefer to provide a surrounding wall preferably substantially cylindrical in form and having 100 a perfectly smooth interior surface to retain the loosened convolutions of the thread at all times, and prevent them from springing away from the spool beyond certain limits and also permitting them to slide down- 105 wardly or upwardly without appreciable friction.

As the means adjacent to the lower end of the spool for preventing the thread from passing or catching under the spool or the 110

body of thread thereon, I prefer to employ what I term a "bedding material," that is to say, a material of such physical characteristics that the lower end of the spool, and 5 in some instances, the lower portion of the body of thread wound thereon, may be slightly embedded into it so as to preclude the possibility of the thread passing under or catching under the spool or the body of 10 thread, said material being also of such character that it will support any portions of the thread which may fall upon it without adhering thereto and without offering any appreciable resistances in case portions 15 thereof directly engage the thread. For this bedding material I preferably employ a granular material, that is to say, a material made up of light granular particles having smooth exterior surfaces and of a character which will not soil white, or the most 20 delicately colored thread, and which will not adhere to the thread or materially impede its progress even if particles of the granular material should be in the way of the thread 25 and have to be slightly displaced in drawing it out. By experiment, I have found that mustard seed is particularly well adapted for this purpose, although I do not limit myself to this particular material, as many 30 other forms of granular material may be found which will answer the same purpose. For example, various other seeds or grains, finely divided particles, preferably spherical, of cork, wood, etc., all of which are within 35 in the scope of my invention. Nor do I limit myself to the use of granular material as in some instances other bedding material may be employed, as for example, certain flocculent materials, fibrous materials or fabrics, 40 the upper surface of which is slightly above the horizontal plane of the bottom of the thread body when the cone or spool is in operative position and is composed of loosely associated, readily displaceable particles so 45 that the lower end of the thread body will be slightly embedded or immersed, as it were, therein and so that the particles of the upper surface of the bedding material may be easily displaced by the thread body and also 50 by the thread drawn off therefrom if it comes in contact with the bedding material or particles thereof, to prevent undue strain from being applied to the thread at any time as it is drawn from the cone or spool. 55 In the drawings, I have shown the preferred embodiment of my invention, which I have selected for the purpose of illustrating the invention, although I do not limit myself to the specific details thereof. In 60 the embodiment herein shown, 1 represents a cup shaped receptacle which is of a form which I have found in actual use to be extremely advantageous, effective and desirable. This receptacle is provided with a 65 supporting bottom, 2, which supports the

bedding material and is preferably provided with a central aperture, 3. The receptacle is also provided with a laterally disposed retaining wall, 4, which is preferably substantially cylindrical and has its upper edge 70 portions provided on the inside thereof with an outwardly and upwardly extending beveled or rounded portion, 5, so that should the thread fall thereon, the edge will not cause the thread to cling or injuriously affect the thread. Within the receptacle, 1, is provided suitable means for supporting a cone or spool and in this instance I have shown means for supporting the paper cone, indicated at 6, on which it is customary to 80 wind thread at the spinning mill, and on which it is customarily furnished to the trade, the said cone being of usual or any preferred construction, and having in this instance a rounded closed top portion, 7, to 85 preclude the possibility of the thread catching on the upper portion of the cone. The cone support herein shown consists of a conical body, 8, ordinarily formed of wood, and supported by a metal spindle or rod, 9, 90 which preferably extends upwardly through the hole, 3, in the bottom of receptacle, 1, and is secured to a bracket, 10, or other supporting device, which also serves to support the receptacle, 1. This bracket, 10, may be 95 of any suitable form and is preferably provided with a circular portion or plate, 11, and the bracket, 10, may be supported in any desired manner adjacent to the knitting machine or other machine to which the 100 thread is to be delivered. Obviously if a wooden spool is used instead of a paper cone, 7, the conical support, 8, may be removed from the spindle, 9, and a wooden spool supported directly on the spindle, 9. 105

Upon the bottom tube of the receptacle is placed the bedding material, which I have shown herein as of granular character and which may be mustard seed, for example, as before stated, and this bedding material indicated at 12 fills up the space below the lower edge of the spool, 6, and below the conical support, 8, in case the latter does not extend entirely to the bottom of the receptacle, and has its upper surface closely adjacent to or very slightly above the lower surface of the body of thread indicated at 15, which is wound upon the cone or spool. 110

In the use of the device the thread will 115 obviously be drawn vertically from the spool and in the drawing I have represented the thread at 15^a as it frequently appears when the tension is relaxed, that is to say, a series of convolutions having sprung away from the body of thread and tending to slip or 120 slide down to the bottom of the receptacle, and I have somewhat exaggerated this in the drawing in order to bring out clearly the operation and utility of the device. It will 125 be seen that the lateral wall, 4, of the recep- 130

tacle retains the convolutions which become loosened from the body of thread and prevent them from falling outside of the receptacle, at the same time affording a perfectly smooth vertically disposed surface which permits them to slide either up or down, and for this purpose the receptacle is preferably made of or lined with glass or porcelain, and I prefer to make it of glass or other transparent material in order that the feed of the thread may be observed at all times through the transparent lateral walls of the receptacle, although this is not essential. It will also be seen that such portions of the thread as fall upon the bedding material are prevented thereby from passing under or catching under the lower end of the spool or cone or the supporting means therefor, or under the body, 15, of thread wound on the spool or cone, so that when the thread, 15^a, is drawn taut it passes without resistance or appreciable friction out of the receptacle and off of the bedding material. Even should the thread, in drawing off of the lower portion of the body, 15, of the thread on the cone or spool, displace particles of the bedding material, the character of the bedding material prevents such displacement from offering any material or appreciable resistance to the thread and immediately settles back in its place.

My invention is admirably adapted for holding cones or spools of artificial silk, used in knitting stockings and other fabrics in which case the device is supported upon a knitting machine in any convenient or preferred manner, and the thread drawn from the cone or spool is led to the feeding devices of the machine. The device is also well adapted for holding cones or spools of artificial silk for use in weaving or for re-winding on to spool cops, bobbins, etc., or for any other purpose for which they may be found convenient, and while as before stated, my improved device is especially adapted for handling artificial silk, it obviously can also be used for holding cones or spools of other thread, if desired.

What I claim and desire to secure by Letters Patent is:

1. A holding device for a cone or spool of artificial silk and other thread, comprising among its members a support for a cone or spool having a horizontally disposed supporting surface and a bedding material located upon said supporting surface, the upper surface of said bedding material being above the horizontal plane of the bottom of the thread body when the cone or spool is in operative position, and being composed of loosely associated, readily displaceable particles whereby the lower end of the cone or spool and the thread body thereon may be embedded in the loose particles of said bedding material, to prevent the

thread from catching under the cone or spool or the body of thread thereon.

2. A holding device for a cone or spool of artificial silk and other thread, comprising among its members a support for engaging and holding the cone or spool, a horizontally disposed part having a supporting surface extending laterally of said support on all sides thereof beyond the periphery of the spool and the body of thread wound thereon, and granular bedding material on said supporting surface having portions adjacent to the lower end of the cone or spool for preventing the loosened thread from catching under the cone or spool or the body of thread wound thereon.

3. A holding device for a cone or spool of artificial silk and other thread, comprising among its members a support for a cone or spool having a horizontally disposed supporting surface and a bedding material composed of loose particles located upon said supporting surface, the upper surface of said bedding material being above the horizontal plane of the bottom of the thread body, whereby the lower end of the cone or spool and the thread body thereon may be embedded in the loose particles of said bedding material, to prevent the thread from catching under the cone or spool, or the body of thread thereon, and a vertically disposed wall extending around the said support above said supporting surface, and engaging said loose bedding material to confine it, and maintain its upper surface at the desired level.

4. A holding device for a cone or spool of artificial silk or other thread comprising among its members a receptacle having a supporting bottom and lateral vertically disposed inclosing walls, a support for engaging and holding a cone or spool within said receptacle, and granular bedding material in the bottom portion of said receptacle and having its upper surface above the plane of the bottom of the spool and the body of thread wound thereon, whereby they may be readily embedded therein, to prevent the thread from catching thereunder as it is drawn off.

5. A holding device for a cone or spool of artificial silk or other thread comprising a receptacle having transparent lateral walls extending above the bottom thereof, a support for a cone or spool within said receptacle and a bedding material composed of loose finely divided particles located in the bottom of said receptacle, and having its upper surface above the plane of the bottom of the body of yarn on said cone or spool to permit the spool and the bottom of the yarn body to be embedded therein, to prevent the yarn from catching under the spool and yarn body as it is drawn off and whereby the entire spool and the yarn there-

on can be seen from a distance in any direction.

6. A holding device for a cone or spool of artificial silk or other thread, comprising
5 a supporting plate provided with a vertically disposed spindle, a receptacle open on the top and having vertically disposed walls, and an aperture in the bottom for the said

spindle, a conical support on said spindle within said receptacle, and granular bedding material in the bottom of said receptacle adapted to surround the lower end of the cone or spool and engage the body of thread wound thereon.

In testimony whereof I affix my signature. 15
JOSEPH HAAS.

It is hereby certified that the assignee in Letters Patent No. 1,168,393, granted January 18, 1916, upon the application of Joseph Haas, of Martinsburg, West Virginia, for an improvement in "Holders for Cones or Spools of Artificial-Silk and other Thread," was erroneously described and specified as "Interwoven Mills, Inc.," whereas said assignee should have been described and specified as *The Interwoven Mills, Inc.*, as shown by the records of assignments in this Office; and that the said Letters Patent should be read with this correction therein that the same may conform to the record of the case in the Patent Office.

Signed and sealed this 8th day of February, A. D., 1916.

[SEAL.]

R. F. WHITEHEAD,

Acting Commissioner of Patents.

Cl. 242—146.
